[57] ABSTRACT

A clip retainer held by a resilient tab in a groove of a hub for limiting the movement of a control valve in the hub and for holding a diaphragm against the hub. Upon actuation of the control valve, fluid under pressure is permitted to flow to one side of the diaphragm. A pressure differential is created across the diaphragm causing the hub to move and transmit a force to an output member.

CLIP RETAINER

BACKGROUND OF THE INVENTION

Servomotors have been used to supply the driving force to move a piston for pressurizing fluid to operate a power braking system for a number of years. To reduce the number of component parts that are needed to produce a servomotor molded parts were developed. As disclosed in U. S. Pat. No. 3,125,003 the movable wall and hub member are molded into a single unit. The control valve carried in the hub is held in place by a stop pin retained in the hub by the diaphragm. Later, as shown in copending U. S. Application Ser. No. 841,628 filed July 14, 1969, now abandoned, the stop pin was replaced by a horseshoe shaped retainer which formed part of the passageway between the variable chamber, but still the position of this stop pin depended upon the tolerance of a groove molded in the hub.

SUMMARY OF THE INVENTION

In subsequent developments it was observed that the snap fitting of the diaphragm against the hub was not necessary since differential pressure across the wall alone would force the diaphragm against the reinforcing plate to prevent communication of fluid pressure between the chambers. Thus, the diaphragm need only be held against the plate by a retainer. I have invented a means of securing the diaphragm to the hub. In my invention a diaphragm retainer is positioned against the reinforcing plate by clip means which partially surrounds the hub. The clip means has an inner projection which fits in a slot in the hub to provide a stop for limiting the extent of movement of the control valve upon release. A tab on the projection will bias the projection against one wall of the slot to prevent any play from developing between the control valve and the projection which would cause noise and unwanted wear between the parts.

It is therefore the object of this invention to provide a servomotor with a single means for retaining the diaphragm against a plate held against the hub and for providing a stop for limiting the movement of the control valve upon release of an actuating member.

It is still a further object of this invention to provide clip means having a resilient member for biasing a projection against a wall of a slot to provide substantially a uniform engagement with a control valve upon release.

It is another object of this invention to provide the means for retaining a wall member against a hub to provide a differential pressure seal between a first and second chamber.

These and other objects will become apparent to those who read the specification and view the drawing.

BRIEF DESCRIPTION OF THE DRAWING

FIG. 1 is a sectional view of a servomotor constructed in accordance with the principles of my invention;

FIG. 2 is a sectional view taken along line 2-2 of FIG. 1 showing the clip retaining means for holding the diaphragm retainer and plate against the hub; and

FIG. 3 is a perspective view of the clip retaining means of the type shown in FIG. 2.

DETAILED DESCRIPTION OF THE PREFERRED EMBODIMENT

The servomotor shown in the FIG. 1 has a housing 10 formed by a front shell 12 and a rear shell 14. The housing 10 is divided by wall means 16 which separates the interior thereof into a power chamber 18 and a control chamber 20. Hub means 22, which is slidably retained in the rear shell 14, is secured to wall means 16. Control valve means 24 upon actuation by push rod 26 by an operator will interrupt communication between the front chamber 18 and the rear chamber 20 by closing passageway 28 and permitting fluid under pressure to flow through internal bore 30 to passageway 32 into rear chamber 20. With fluid in the rear chamber 20 at a different pressure than the fluid in front chamber 18, a differential pressure force will be created across wall means 16. This differential pressure force will be transmitted to the hub means 22 to cause it to move. When the hub means 22 moves, an output force for pressurizing a master cylinder in a braking system (not shown) will be produced.

In more particular detail the hub means 22 includes, a cylindrical boss 34 with a land 37 adjacent a shoulder 36 located in the internal stepped bore 30. A slot 38 adjacent the land 37 adjacent a shoulder 36 extends to the periphery of the cylindrical boss 34. A radially extending flange 40 having a first groove 42 concentric to the flange 40 and a second groove 44 of an inverted key-hole shape, shown in FIG. 2, surrounds the cylindrical boss 22.

The wall means 16 has a flexible diaphragm 46 which has a first bead 48 sealingly retained between the front shell 12 and the rear shell 14 by periodically having wing 50 crimped down against edge 52 of the front shell 12. A second bead 54 of the diaphragm mates with concentric rib 56 of the reinforcing plate 57. The reinforcing plate 57 has a smooth outer rim 59 which substantially conforms to the cylindrical shape of the housing 10 and an inner edge 65 which conforms with the inverted key-hole shaped groove 44. A cylindrical retainer member 64 having a similar inverted key-hole shape holds the second bead 54 of the diaphragm in the arcuate rib 56 of the plate.

The control valve means 24 located in the internal stepped bore 30 has a plunger member 61 which includes a keeper member 58 on the front face and a rearwardly facing annular atmospheric valve seat 60 thereon on the rear face for sealing abutment with a flexible annular rubber poppet member 62. The annular rubber poppet member 62 surrounds a matching tube 63 which transmits an actuation force to seat the poppet member 62. The poppet member 62 has an integral flexible diaphragm portion 66 with a radial outer periphery 68 which is enlarged for sealing engagement with the sidewalls of the internal stepped bore 30. The rubber poppet member 62 is biased against the atmospheric valve seat 60 by a coil spring 70 that surrounds the push rod 26 and is interposed between flange 72 and shoulder 74. The control valve means 24 is retained in the deactivated position, as shown in FIG. 1, by a return spring 76 positioned between a retainer 78 held on push rod 26 by shoulder 74 and a sealing annular washer 80 which biases the outer thickened portion 68 into sealing engagement with the sidewalls.

Upon actuation of the valve means 24 by push rod 26 the keeper member 58 slides along the land 37 with the flexible rubber poppet 62 first seating on shoulder 82 which closes communication between the front chamber 18 and the rear chamber 20 and then the valve seat 60 moves away from the poppet 62 to permit atmospheric pressure access to chamber 30 from whence it flows through passageway 32 into the rear chamber 20 to create the pressure differential for operating the servomotor.

When the push rod 26 is released, the force of the return spring 76 will move the valve means 24 to the right as viewed in FIG. 1. To maintain the valve means 24 in the proper operating position in the bore 30, a clip retaining means 84 is positioned in slot 38. The clip retaining means 84 has a pair of prongs 86, and 87, as shown in FIGS. 2 and 3, which surround the stem section 88 of the keeper member 58 to provide a substantial uniform support around the end keeper member 58 for stopping rearward movement when the valve means 24 is released. Tab 98 secured to the center of clip retaining means will resiliently bias prongs 86 and 87 against one side of the slot 38 to assure the keeper member is stopped in the same location after each application. By maintaining the prongs 86 and 87 snug against the slot 38, the possibility of a rattle between the parts and uneven wear on the parts is reduced after repeated use. The clip retaining means 84 has a central arcuate portion 90 which extends past the periphery of the cylindrical boss 34 to hold plate retaining means 64 tight against the reinforcing plate 57. A pair of arms 94 and 96 attached to the central arcuate portion 90 of the clip retaining means 84 has a shape to substantially conform to the arcuate portion of the inverted key-hole shaped section of the boss 34 and end section 65 of the diaphragm plate 57. Each of the arms 94 and 96 has a projection 97 which snaps into an indentation 100 on the cylindrical boss 34 to fix the position of the clip retaining means 84 in the inserted position. Each of the arms 94 and 96 in conjunction with the central arcuate portion 90 help to hold retainer member 64 tight against the reinforcing plate 57 and seal 92 in the first groove 42 to assure a seal between the front and rear chambers 18 and 20, respectively. Each of the arms 94 and 96 are identical to assure a tight fit even though in the process of assembly the location of the tab 98 may in slot 38 be reversed. Thus, the clip retaining means 84 will perform the dual duty of limiting the movement of the control valve and holding the diaphragm against the reinforcing plate to provide a way of easily constructing a useable servomotor.

I claim:

1. In a servomotor having a housing divided by wall means into a control chamber and a power chamber and operated by a control valve which allows fluid pressure into the control chamber to create a pressure differential between the control chamber and the power chamber causing the wall means to move and transmit a force to an output rod, the wall means including a flexible diaphragm, means for connecting the wall means to the output rod and for holding the control valve in an operative position, said means comprising:

hub means having a stepped internal bore, said internal bore being connected to said control chamber and power chamber by passages through which

said fluid under pressure flows, said hub means having a radially extending external flange extending along the inner diameter of said flexible diaphragm, said output rod being retained against a reaction member which abuts a shoulder of a land in said internal bore, said hub means having a slot adjacent said land extending to the periphery of said hub;

keeper means attached to the control valve, said keeper means being located to slide in an axial direction through the width of said land to position said valve means within said internal bore; and clip means located in said slot having a central portion which extends into said internal bore to surround said control valve for limiting the extent of axial movement of said keeper means to substantially the width of the land within said internal bore, said central portion having an arcuate projection extending past the periphery of said hub means at said slot, said clip means having a pair of arms secured to said arcuate projection, each of said arms having a portion which snaps into a groove in said hub means to lock said clip means in a fixed position to retain said flexible diaphragm against said external flange, said external flange transferring the force created by said pressure differential through the hub means to said output rod.

2. In the servomotor, as recited in claim 1, wherein the central portion of said clip member includes:

a resilient tab member for biasing said central portion in said slot to inhibit axial movement of said central portion corresponding to movement of said keeper means.

3. In the servomotor, as recited in claim 2, further including:

plate means having a central opening which surrounds said hub adjacent said external flange with a radially extending surface, said radially extending surface terminating in a peripheral rim substantially concentric to said housing of the servomotor; and

a seal located between plate means and said external flange for preventing fluid pressure from passing from the control chamber to the power chamber, said plate means having a concentric rib which urges said seal against said flange.

4. In the servomotor, as recited in claim 3, wherein said flexible diaphragm includes:

a first bead secured to the housing of said servomotor with a central portion overlying said plate means and a second bead which mates with said concentric rib; and

a retainer member located between the arcuate projection on said clip means and said plate means for holding said second bead against said rib to maintain a seal between said control and said power chambers.

5. In the servomotor, as recited in claim 4, wherein said pair of arms act on said retainer member to hold said bead in said rib.

6. In the servomotor, as recited in claim 5, wherein said central portion of said clip member extending into said bore includes:

a pair of prongs having a curved section for abutting the interior of said bore when said arms are snapped in a locked position;

3,688,647
